UNITED STATES PATENT OFFICE.

FREDERICK H. KNAPP, OF BALTIMORE, AND HAYWOOD G. DEWEY, OF WESTMINSTER, MARYLAND, ASSIGNORS TO FRED. H. KNAPP COMPANY, OF WESTMINSTER, MARYLAND, A CORPORATION OF MARYLAND.

CAN-WRAPPING MACHINE.

1,370,750.

Specification of Letters Patent.

Patented Mar. 8, 1921.

Application filed February 5, 1916. Serial No. 76,437.

To all whom it may concern:

Be it known that we, FREDERICK H. KNAPP, a citizen of the United States, residing at Baltimore, State of Maryland, and 5 HAYWOOD G. DEWEY, a citizen of the United States, residing at Westminster, in the county of Carroll and State of Maryland, have invented certain new and useful Improvements in Can-Wrapping Machines, of 10 which the following is a specification, reference being had therein to the accompanying drawing.

This invention relates to labeling machines, of a character adapted to apply and 15 affix labels to cans, cartons, or the like.

One of the main objects of the present invention is to provide novel and improved can stopping and escapement mechanism, quite useful wherever applicable, for instance at either the inlet or discharge end 20 of a labeling mechanism, and said escapement mechanism being of a positive and highly efficient character, as well as strong and durable in use.

25 Further the invention includes can stopping and escapement means of improved construction adapted more especially for the forward or can inlet end of the machine, said escapement means including a member or members movable into and out of the path of a foremost can, and having operatively associated therewith an auxiliary can stopping member, adapted to move into and out of the path of succeeding cans, the said 30 members being so constructed and arranged that as the first mentioned member is moved out of the path of the foremost can to release the same, the second mentioned member is moved into the path of succeeding cans to interrupt the movement 35 thereof.

It is also contemplated by the invention to provide novel and improved can stopping and escapement mechanism at the discharge end of the labeling machine proper, said escapement mechanism in the embodiment of the invention herein illustrated having associated means for delivering the labeled cans one at a time from the labeling mechanism. In the present embodiment of the invention, the said can delivery means is adapted to directly transfer a la-

beled can to suitable mechanism for folding projecting edges of the label over the ends of the cans.

The invention in its preferred embodiment is illustrated and described herein as having more particular reference to a combined can labeling and wrapping mechanism, that is to say a machine having mechanism to apply and affix about the periphery of a can a label, the edges of which project beyond opposite ends of the can, and mechanism to fold said projecting edges over and in snug contact with the ends of the can, and the invention in this particular includes means whereby the said labeling mechanism and folding mechanism may be readily detached from one another to the end that either of said mechanisms may be independently operated, the one as a labeling machine and the other as a wrapping machine.

A further feature of the invention resides in the provision of novel and improved pasting mechanism adapted to apply paste, cement or the like to the periphery of the cans at the edges thereof, which is of especial advantage and usefulness in that embodiment of the invention wherein a mechanism is employed to fold the projecting edges of the label over the ends of the can, it having been ascertained that when the label is secured to the can at its edges, the same may be more readily and neatly folded without the likelihood of breaking or damaging the label at this point.

Other and further improvements, and novel details in the construction and arrangement of the various parts of the invention will be appreciated from the description to follow which for a clear understanding thereof is to be considered in connection with the accompanying drawings forming a part thereof and wherein is disclosed for the purpose of illustration a convenient and satisfactory embodiment thereof.

In the drawings:

Figure 1 is a front elevation of the machine;

Figs. 2 and 3 are detail views enlarged of the can feed and escapement mechanism at the outlet end of the machine;

Figs. 4 and 5 are detail views enlarged

of the can feed and escapement mechanism at the inlet end of the machine;

Fig. 6 is an enlarged detail view showing more particularly the actuating means of 5 the escapement mechanism at the discharge end of the machine.

Fig. 7 is a detail view of the can pasting roll.

With more particular reference to the 10 drawings wherein like reference numerals refer to corresponding parts throughout the several views, 1 is a supporting frame mounted upon suitable legs or standards 2 conveniently having roller supports 3 at the 15 base thereof. 4 is a can feed runway or chute at the forward end of the machine. As is usual in this type of machine, the feed chute or runway is preferably supported at a downward inclination toward the front 20 end of the machine, and said runway may be pivoted to the framework in any desired manner, whereby when the machine is not in use, the runway may assume an upright position against the front end of 25 the machine, as usual. Suitable main runway bars 5 are supported in any desired manner upon the framework of the machine, and suitable guides for the ends of the can comprise a stationary guide bar 6 and an 30 oppositely disposed yieldable guide bar 7, the latter being preferably of sheet metal, whereby the same may yield at any point throughout its length, and the said bar 7 be yieldably supported as by spiral springs. 35 The stationary guide bar 6 as well as the yieldable guide bar in the embodiment of the invention herein illustrated preferably terminate at the forward edge of the label receptacle, the forward end of the guide bar 40 6 having an upwardly and rearwardly curved extension 8 for a purpose to be hereinafter more particularly described.

The label support 9 is of a character to support, if desired, labels of a width to 45 project beyond the ends of the can, said projecting ends to be hereafter folded over the ends of the can by suitable folding mechanism generally indicated by the numeral 10, the specific construction of such 50 folding mechanism forming the basis of a separate application for patent filed concurrently herewith. The runway bars 5 at points overlying the label receptacle are cut-away whereby to permit the cans to contact directly with the labels in the receptacle and pick up the uppermost label, it being 55 observed that the cans previously have had applied thereto paste for picking up the labels. Adjacent the rear end of the label 60 receptacle is a lap end pasting mechanism 11 of any approved type.

The means for moving the cans along the runway preferably takes the form of one or more endless belts or conveyers 12 mounted 65 upon suitable roller supports 13 and 14, the

roller support 13 constituting a drive wheel for the various movable parts of the apparatus, said wheel being fixed upon a shaft 15 which latter is driven in any desired manner as by power mechanism or a suitable 70 handle connected thereto.

In view of the fact that the labeling mechanism generally indicated by the numeral α and including the automatic feed for the label support, the lap end pasting mechanism 75 and the driving mechanism for these parts is preferably substantially the same construction as that illustrated and described in the patent to Knapp and Dewey, No. 1,271,724, application for which was filed February 5, 80 1915, it is deemed unnecessary to specifically describe the same herein. Likewise in the same patent is illustrated and described the endless belt-supporting mechanism and the driving connection therebetween and the 85 other parts of the mechanism including the labeling mechanism, and it is not necessary to refer to the same in detail herein, no claims being predicated specifically on these 90 features.

Arranged forwardly of the labeling mechanism is suitable pick up pasting mechanism including a paste pot or receptacle 16 detachably supported as by hangers 17 upon the runway bars 5, said pot being adapted 95 to contain paste or cement adapted to be delivered directly on to the can. Mounted in the paste pot is a suitable pasting device comprising a rotatable shaft 18 mounted in suitable bearings, one end of the shaft projecting beyond the side of the paste pot and having suitable gear connection 19 with the shaft of the roller support 14 in any desired manner. The pasting device proper includes a series of annular center disks 20 and end 100 disks 21, the latter being separated from the center disks by intervening spaces, and all of said disks being preferably connected to an integral hub 22. It is desirable in the present instance to apply paste to the cans 110 at the extreme outer edges thereof and the end paste disks 21 are designed primarily for this purpose. By reason of this peculiar type of pasting mechanism, it will be observed that the label will be secured at 115 the extreme outer edges of the can when the same are picked up by the can in the rolling movement of the latter along the runway, and this is of material importance particularly where the labels to be applied are of 120 a length to project beyond the ends of the can to be operated upon by the folding mechanism 10.

The labels being tacked to the can at the extreme edges thereof coöperate with the 125 folding mechanism to insure a neat and smooth fold and obviate the likelihood of breaking or wrinkling the label at this point in the folding operation. To accommodate for the pasting mechanism engaging the can 130

at the edges thereof, the runway bars 5 have suitable cut-out parts 23, the end disks 21 being positioned in the space formed by said cut-out parts and forming in effect, a continuation of the can runway bars 5 for supporting the can in its movement along the runway. A suitable paste scraper member 24 is adjustably mounted as by bolt and slot connection 25 upon the paste pot and regulates the amount of paste taken up by the various disks 20-21.

From the description thus far, it will be noted that as the cans are fed along the runway bars 5, through the medium of the endless carriers 12, the cans come in contact with the pasting disks 20-21, spots or daubs of paste being taken up by the can at the center and outer edges thereof, and in the continued movement of the can, the pasted area thereof will contact with the forward edge of the uppermost label on the support, the support being periodically fed upwardly to accommodate for the diminishing supply thereof. As previously described, the label support is of a character to accommodate labels of a width greater than the length of the cans, and this makes necessary terminating the guide bars 6 and 7 at the forward end of the label support, the guide bar 6 however, having the curved extension 8 thereby accurately positioning the can with regard to the label, and because of the curved character of said extension 8 the projecting edges of the label which has been picked up by the can will, in the rolling movement of the can, pass under the curved surface of the extension, without being displaced or injured. Obviously the opposite guide bar 7 may have a similar curved extension 8, if desired. The continued movement of the can over the label receptacle, which latter takes the place of the runway bars 5, at this point causes the label to wrap about the can, and the lapped end of the label having previously been supplied with paste through the medium of the lapped end pasting mechanism 11, said lapped end of the label will overlie the oppositely attached end of the label and be secured in place.

Arranged above the runway and at a point between the conveyer belts 12 is a suitable yieldable member preferably taking the form of a brush 25 adapted to yieldably engage the periphery of the labeled can and thereby tend to smooth out any wrinkles in the label.

Arranged rearwardly of the brush member 25 and in a cut-out part of the runway bars 5 is a suitable yieldable pad 26 of a length extending from end to end of the can, which said pad is preferably arranged in substantially vertical alinement with the feed belt supporting rolls 13, with the result that as the labeled can moves over the yieldable pad 26, the rollers 13 will tend to iron

the label and firmly affix the pasted portions thereof to the can.

At the rear end of the runway bars 5, there is provided a suitable receiving pocket or stop for the cans, the same being preferably formed by relatively wide segmental plates 28 secured one to each of the terminals of the bars 5, the bars 5 at their points of connection with said plates 28 preferably inclining downwardly toward said plates 75 and the plates forming a depression in the runway with the free portions thereof projecting a considerable distance above the plane of the runway thereby affording a substantial stop for the cans. The cans may 80 be lifted from said stop by any desirable mechanism, or even by the hand of the operator. More particularly, is this true, assuming that the folding mechanism is not to be employed and that the labels which are 85 applied to the cans are not of a character to project beyond the edges to be folded against the ends of the can in which event the labeling operation will be complete when the cans reach a position in the receiving 90 pocket 28. In the preferred embodiment of the invention, however, it is contemplated to not only label, but wrap the cans, and with this in view, suitable transfer mechanism is provided for picking up a labeled can from 95 the pocket 28 and delivering the same directly into the folding mechanism 10, said pick up mechanism as illustrated, taking the form of a rotatable reel or carrier wheel 30 having a series of segmental pockets 31 in 100 the periphery thereof, said wheel being of a character to project into the space between the segmental plates 28, and the operation of said wheel being so timed that when a can assumes a position in the pocket formed 105 by said plate 28 a segmental part 31 of the wheel will engage about the periphery of the can when the same will be lifted out of said pocket and fed directly to the folding mechanism, as will be more clearly appreciated from the illustration and description of the folding mechanism *per se* which constitutes the subject-matter of the separate application filed concurrently herewith.

The wheel 30 and associated parts of the 115 folding mechanism are mounted on a suitable framework 32 having suitable roller supports 33 at the base thereof and said framework being detachably connected in any desired manner when properly positioned as 120 by bolts 32^a to the framework 7 of the labeling mechanism proper. Likewise, the wheel 30 and associated movable parts are adapted to be driven directly from the same power which drives the various movable 125 parts of the labeling mechanism heretofore described, a suitable drive shaft 34 having gear connection 35 with certain of the driven parts of the labeling mechanism, has a detachable universal coupling mechanism 36 130

with a drive shaft 37 adapted to actuate the various movable parts of the folding mechanism.

In order to separate succeeding cans and interrupt the movement thereof while a foremost can is in the pocket 28 to be picked up by the conveyer member 30 of the folding mechanism, there is provided suitable can stopping or spacing mechanism preferably of the following construction:

39 is a suitable roller member mounted for free rotation upon a shaft 38 which latter in turn is connected to a downwardly projecting bracket extension 40 at the outer free end of a rock arm 41, the latter taking the form of a bell crank lever, the opposite end thereof being illustrated at 42. The roller members 39 preferably comprise a plurality of separated rolls as illustrated more particularly in Fig. 2 and conveniently the bell crank lever 41 and associated parts are duplicated, the two members being connected to one another as by a transverse bar 43. The bell crank levers 41-42 are loosely mounted upon a shaft 44 which shaft may be an integral extension of the shaft 16 which supports the feed belt rolls 13. Because of the elongated character of the rock arm 41 and parts carried thereby, it will be observed that the roller or free end of said arm will move downwardly by gravity, and this downward movement is limited by a suitable adjustable stop 45 in the form of a threaded bolt mounted in a rearward extension 46 of the rock arm, the said bolt being adapted to engage a suitable stop or abutment 47 secured to the framework of the machine in any desired manner. By adjusting the bolt 45, the downward limit of movement of the rollers 39 may be varied as desired. The means for actuating the rock arm 41 will now be described, it being noted in this connection, however, that minor changes in details of construction may be resorted to without departing from the spirit of the invention.

Mounted upon the shaft 16 is a suitable pinion 48, the same adapted to mesh with a suitable gear 49 mounted upon a stub-shaft 50 rotatably mounted in any desired manner on the framework of the machine. Fixed to said stub-shaft is a suitable cam disk 51, the same adapted at its periphery to be engaged by a roller bearing 52 projecting laterally from a coupling lever 53 pivoted at 54 upon an elongated reciprocating arm or bar 55. The reciprocating arm 55 is slotted intermediate its ends at 55^a and is mounted upon the shaft 50 at this point, the said arm being pivotally connected at one end at 56 with the upper end of the extension 42 of the bell crank lever.

A suitable spiral spring 57 connected at one end 58 to the coupling lever 53 and at

its opposite end to a pin 59 on the reciprocating arm 55 tends to normally hold the coupling lever in one of its positions of movement, and a cut-out portion 60 adapted to engage the pin 59 serves to lock the arm 55 against rearward movement at a time when the rollers at the free end of the bell crank levers 41-42 are in lowermost or can separating and stopping position. In order to elevate the rollers out of the path of the cans to permit succeeding cans to move into one of the pockets 31 of the rotatable reel 30 of the folding mechanism, the cam 51 in its rotatable movement in contact with the roller 52, will move the locking end 60 of the coupling lever 53 out of locking position, this end of the coupling lever being elevated for this purpose, and the opposite offset end 61 of the coupling lever being adapted to contact with a stop or abutment 62 at the free end of the reciprocating arm 55. The coupling lever 53 at this time constitutes in effect a fixed part of the reciprocating arm 55 with the result that the continued movement of the cam 51 disk will impart rearward movement to the reciprocating arm and tilt the bell crank lever 41-42 about the pivotal support 16-44, thereby elevating the roller end of the rocking arms.

The operation of the last described can stopping and releasing mechanism may be reviewed as follows:

Assuming that the shaft 50 is being rotated by its pinion and gear connection with the shaft 16, and that the rollers 39 are in elevated position or out of the path of the cans, a foremost can will fall into the can receiving pocket 28 of the runway. At this time, it is desirable to lower the rollers 39 into contact with the foremost can and between the foremost can and the next succeeding can, thereby separating these cans and interrupting the continued movement of the succeeding cans while the foremost roll is being rotated out of the pocket by the rotatable reel moving in the space between the oppositely disposed members 28 of the pocket. The cam disk 51 when the rollers 39 are in upward position, will act to maintain the coupling lever 53 with its end 61 in contact with the abutment 62. The continued rotation of the cam 51 will bring a reduced portion of said cam into contact with the roller 52 of the coupling lever, thereby allowing the roller or weighted end of the rock arms 41-42 to gradually lower, by gravity, into lowermost position and when the limit of the lowering movement of the rollers is reached, a further reduced portion of the cam 51 will permit the spring 57 to move the coupling lever 53 about the pivot 54 when the locking end 60 of said coupling lever will contact with the stop 59. Because of the construction of cam, the rollers 39

- will be maintained in lowered locked position for sufficient interval to permit of the foremost can being elevated out of the pocket and moved into position to be acted 5 upon by the folding mechanism proper. After sufficient interval has elapsed a raised portion of the cam 51 in contact with the roller 52 will tend to rock the coupling lever out of locking position with the stop 59, and 10 after the opposite end 61 of the lever contacts with the stop 62 the reciprocating lever 55 will be moved rearwardly by the cam in the manner previously described, which results in upward releasing movement of the 15 rolls 39.
- Another feature of the invention resides in novel spacing mechanism at the inlet end of the machine, said mechanism being adapted to cause the delivery of the cans one at 20 a time, from the feed chute or runway to the main runway of the machine, to the end that the cans may be individually operated upon by the various pasting and labeling means heretofore referred to. This spacing 25 mechanism is of a character somewhat similar to that heretofore described as arranged at the discharge end of the labeling machine, and it is unnecessary to describe in detail the construction and operation of these parts 30 which may be readily understood and followed from the description above, the parts of the escapement mechanism at the forward end of the machine which correspond to the same parts at the rear end of the machine 35 being given the same reference character numeral in the drawing with an alphabetical exponent. In that embodiment of the spacing mechanism at the forward end of the machine, the roller members 39^a are adapted 40 in the lowered position of the rock arms 41^a—42^a to contact the foremost can forwardly of the latter. Loosely connected for rocking movement upon the shaft 38^a of the rollers 39^a are arms 65 separated from one 45 another a sufficient distance to overlie the ends of the cans, and said arms being connected at the free end thereof by a stop bar 66. Pivotaly connected to said arms 65, intermediate the ends thereof, are inclined 50 upright supports 67 having a slotted portion 68 at the lower end thereof adapted to engage over suitable pin projections 69 on the framework of the machine. The normal position of the arms 65 and supporting 55 members 67 when the rollers 39^a are in position to stop the foremost can, is illustrated more particularly in Figs. 1 and 4. Now as the roller members 39^a are elevated out of the path of the foremost can in the manner 60 heretofore described, the stop bars 66 being guided by the supporting members 67 will be lowered into a position between the foremost can and the next succeeding can and maintained in this position, whereby to interrupt the movement of succeeding cans, 65 until the forward can has moved along the main runway the proper distance, when the roller members 39 will be lowered and the stop bar 66 elevated, allowing succeeding cans to move down the chute until the same 70 contact with the rollers 39^a.
- The respective can stopping and escape- 75 ment means at the opposite ends of the labeling machine proper are so timed that as the roller members 39^a are in lowered position or in the path of the cans, to interrupt the movement thereof at the feed or inlet end of the machine, the roller members 39 at the opposite end of the machine will be elevated to permit the escape of a can, it being 80 preferred and in the illustrated embodiment of the invention, the parts are arranged whereby to have but one can at a time in operative association with the labeling mechanism. 85
- The roller members 39 and 39^a constitute anti-friction engaging surfaces readily riding over the cans as the latter are released thereby.
- Should it be desired to utilize the labeling 90 mechanism to the exclusion of the folding mechanism, it will only be necessary to release the detachable securing bolts 32^a connecting the respective frames 1 and 32 and to release the drive coupling means 36, when 95 the labeling machine and folding machine may be independently operated as such.
- In the description and claims wherein the term "cans" is employed as referring to the article to be labeled or wrapped, this term 100 is to be construed as a general one including within its scope any character or type of carton, package, etc., in the labeling of which the machine may be found useful.
- What is claimed as new is:— 105
1. In a labeling machine having a runway for cans, and labeling mechanism intermediate the ends of the runway, the combination of connected members, one of which is adapted to engage in front of a foremost can and the other forming separating means to engage between said foremost can and succeeding cans in the runway, and means whereby as one member is moved to can releasing position the other is moved into can holding position, the foremost can engaging member comprising an anti-friction device whereby to facilitate the release of the roller from its engaged can, and the other member adapted to remain in can holding position during the labeling of the foremost can. 110
  2. In a labeling machine having a can runway and labeling mechanism, the combination of can feeding and stopping mecha- 125 nism, comprising an arm positioned above the runway and mounted for swinging movement, means carried by the arm to move into the path of the foremost can and interrupt the movement thereof, means for 130

moving said arm to release the can, and means also carried by the arm to engage between the released can and the next succeeding can to interrupt the movement thereof, and releasable means for locking said member in one of the adjusted positions thereof whereby successive cans are released only after a preceding can has been labeled.

3. In a labeling machine, having a runway and labeling mechanism, the combination of means for feeding cans along the runway, and means for interrupting the movement of cans along the runway, comprising a member above the runway and movable by gravity into a position in the path of the cans, and means for locking the member in this position, said means being releasable and governed by the can feed means.

20 4. In a labeling machine having a can runway and labeling mechanism, the combination of means for feeding the cans along the runway into operative association with the labeling mechanism, means for interrupting the movement of cans along the runway comprising a roller, gravity actuating means for moving the roller into a position to interrupt the movement of the cans, means for locking the roller in the last mentioned position, means operatively associated with the can feeding means for releasing the roller and moving the same out of the path of the cans along the runway when released.

25 5. In a labeling machine having a runway for cans, labeling mechanism and means for feeding cans along the runway into operative association with the labeling mechanism, the combination of means arranged above the runway to interrupt the movement of cans along the runway and comprising a rock arm support pivotally mounted intermediate its end, a roller at the free end of said arm adapted to move by 30 gravity downwardly into the path of the cans, and releasable locking means operatively associated with the can feeding means for maintaining the roller in can engaging position for a predetermined interval.

35 6. In a labeling machine having a label mechanism, the combination of a runway along which cans are adapted to roll to and from said mechanism, and means for interrupting the movement of cans along the runway comprising an arm support loosely mounted for rocking movement, a roller at one end of said arm arranged to be positioned in the path of a can along the runway, means at the opposite end of said arm 40 to move the roller out of the path of the cans, and means operatively associated with the last mentioned means for locking the arm in one of its adjusted positions.

45 7. In a labeling machine having a runway for cans, labeling mechanism and means for

feeding the cans along the runway into operative association with the labeling mechanism, the combination of means arranged above the runway to interrupt the movement of cans along the runway and comprising a rock arm, a roller at the free end of said arm adapted to move by gravity downwardly into the path of the cans, and releasable locking means operatively associated with the can-feeding means for maintaining the roller in engaging position for a predetermined interval.

8. In a labeling machine having a labeling mechanism, the combination of a runway along which cans are adapted to roll to 50 and from said mechanism, and means for interrupting the movement of cans along the runway comprising an arm support loosely mounted for rocking movement, a roller at one end of said arm arranged to be positioned in the path of a can along the runway, means adjacent the opposite end of said arm to move the roller out of the path of the cans, and means operatively associated with the last-mentioned means for temporarily locking the arm with the roller in the path of a can along the runway.

9. An attachment for labeling machines having labeling mechanism and a runway along which cans are adapted to roll, said attachment comprising means for interrupting the movement of cans along the runway comprising a rock arm support loosely mounted for rocking movement, a roller at one end of said arm arranged to be positioned in the path of a can along the runway, a can feeding mechanism above the runway including a rotatable shaft, and means operatively associated with said shaft and moved thereby to actuate said arm.

10. An attachment for labeling machines having labeling mechanism and a runway along which cans are adapted to roll to said mechanism, said attachment comprising an arm mounted for rocking movement above 100 the runway, a roller at the end of the arm to engage and interrupt the movement of cans along the runway, means whereby said arm is moved into the path of the cans by gravity, and means for limiting the downward movement of said arm, releasable means for maintaining said arm in lowered position and means for raising the arm with the roller out of the path of the cans.

11. An attachment for labeling machines, 110 having labeling mechanism and a runway for feeding cans to and from said mechanism, the attachment comprising means for interrupting the movement of cans along the runway comprising a roller, a bell crank 115 lever pivotally mounted at its elbow, said roller being mounted at one end of the lever, and a movable arm to engage said lever at its opposite end and actuate the same.

12. An attachment for labeling machines,

having labeling mechanism, and a runway for feeding cans to and from the mechanism, said attachment comprising means for interrupting the movement of cans along the runway comprising a bell crank lever pivotally mounted at its elbow to a stationary support, means mounted upon one end of the lever to engage and interrupt the movement of a can along the runway, a reciprocating arm to engage the opposite end of said lever to actuate the same, and cam actuating means for the reciprocating arm.

13. An attachment for labeling machines, having a runway for cans and labeling mechanism intermediate the ends of the runway and in the path of the cans, said attachment comprising means for interrupting the movement of cans along the runway comprising a bell crank lever pivotally mounted at its elbow to a stationary support, means mounted upon one end of the lever to engage and interrupt the movement of a can along the runway, a reciprocating arm, to engage the opposite end of said lever to actuate the same, and locking means operatively associated with the lever to maintain the same in one of its positions of movement.

14. An attachment for labeling machines, having a runway for cans and labeling mechanism in the path of the cans intermediate the ends of the runway, said attachment comprising means for interrupting the movement of cans along the runway comprising a bell crank lever pivotally mounted at its elbow to a stationary support, means mounted upon one end of the lever to engage and interrupt the movement of a can along the runway, a reciprocating arm to engage the opposite end of said lever to actuate the same, locking means operatively associated with the lever to maintain the same in one of its positions of movement, and cam actuating means for releasing said locking means and imparting movement to the lever.

15. An attachment for labeling machines, having labeling mechanism and a runway for feeding cans to and from said mechanism, the attachment comprising means for interrupting the movement of cans along the runway comprising a roller, a bell-crank lever pivotally mounted at its elbow, said roller being mounted at one end of the lever and adapted to move by gravity in one direction, and a movable arm to engage said lever at its opposite end and actuate the roller in an opposite direction.

16. In a machine of the character described, the combination of a runway, pasting and labeling mechanism, and can stopping means arranged adjacent opposite ends of the runway, said can-stopping means being adapted to actuate by gravity in one direction, positive means for moving the

stopping means in an opposite direction, and means whereby the can-stopping means at opposite ends of the runway are alternately movable into and out of the path of the cans on the runway.

17. In a labeling machine, having labeling mechanism, and a runway extending to said mechanism, the combination of means for feeding cans along the runway to and from said mechanism, and means for interrupting movement of cans along the runway comprising a movable member, a rotatable cam, a reciprocating arm connected to said movable member and cam engaging means mounted upon said arm, and releasable locking means for said movable member operatively associated with said can feeding means and said cam engaging means.

18. An attachment for labeling machines, having labeling mechanism and a runway leading to and from said mechanism, said attachment comprising means for feeding cans along the runway, a can stop arranged above the runway comprising a rocking member, and means for rocking said member including a rotatable shaft operatively associated with the can feeding means, a cam on the shaft, a reciprocating arm having a slotted engagement with the cam shaft, and a pivoted lever mounted on the reciprocating arm and having means to engage the cam.

19. In a labeling machine having labeling mechanism, a can runway and means for moving the cans along the runway, the combination of a can stop arranged above the runway comprising means movable into and out of the path of a foremost can, a substantially U-shaped member pivotally supported at its arms to said means, and supporting means for said member comprising an arm pivoted to one of the arms of said U-shaped member and having a loose support at its opposite end, said arm being adapted to cause the member to move in the path of succeeding cans as said means is moved to releasing position.

20. In a labeling machine having labeling mechanism and a can runway, the combination of a can stop arranged above the runway comprising means movable into and out of the path of a foremost can, a substantially U-shaped member pivotally supported at its arms to said means, and supporting means for said member comprising upright supports having a pin and slot connection at the lower end and pivotally connected at their upper end to the arms of the U-shaped member.

21. In a labeling machine, a runway for cans comprising opposed bars having a cut-out part in the inner side thereof, labeling instrumentalities, and pasting mechanism including a roll having a series of center disks to engage the periphery of the can at

- the center thereof, and end disks arranged to project into said cut-out parts in the sides of the said runway bars to engage the edges of the can.
- 5 22. In a machine of the character described, the combination of a runway having segmental extensions forming a pocket adjacent the rear end thereof to receive a can from said runway, and a movable can stop above the runway adjacent said segmental extensions.
- 10 23. In a machine of the character described, the combination of a runway for cans or the like, pasting mechanism, labeling mechanism, opposed segmental extensions connecting with the rear end of the runway forming a receiving pocket for labeled cans, and can transfer mechanism movable between said opposed segmental sections.
- 15 24. In a machine of the character described, the combination of a runway for cans or the like, pasting mechanism, label-

ing mechanism, opposed members connecting with the runway forming a receiving pocket for labeled cans, can transfer mechanism movable between said opposed members, and a movable can stop arranged above said opposed members adjacent the forward end thereof.

25 25. In a machine of the character described, the combination of a runway, pasting and labeling mechanism, and can stopping means arranged adjacent opposite ends of the runway, said means being alternately movable into and out of the path of the cans on the runway.

In testimony whereof we hereunto affix our signatures in the presence of two witnesses.

FREDERICK H. KNAPP.
HAYWOOD G. DEWEY.
